UNITED STATES PATENT OFFICE

JACQUES OLLENDORFF, OF PARIS, FRANCE, ASSIGNOR TO ANCIENS ETABLISSEMENTS R. CORNELY & CO., SOCIÉTÉ ANONYME, OF PARIS, FRANCE, A COMPANY OF FRANCE

SEWING MACHINE

Application filed February 10, 1928, Serial No. 253,377, and in France July 27, 1927.

In sewing machines of the double-needle type, and chiefly in machines adapted for open-work, in which the two loopers with vertical axes are placed symmetrically on either side of the axis of the needle-carrier and rotate in opposite directions in such manner as to form absolutely symmetrical rows of stitches, it is observed that when the speed of the machine exceeds a certain limit, the two loops formed by the two threads of the needle are at a certain stage of the formation of the stitch thrown violently together; the said loops thus make contact with one another and become entangled, so that the yarn will break when it is drawn back by the tension device.

In the present invention I obviate this defect by placing a partition between the loops formed by the two needle threads whereby all contact between the said threads will be prevented, so that the sewing can be effected at a high rate of speed.

The said partition may be variously constructed and may consist of a metal plate which is secured in the fixed position upon a suitable part of the machine, or may on the contrary be made removable and interchangeable.

Fig. 1 shows in a machine of the type above indicated the stage of the formation of the stitch in which the two loops are thrown violently together and shows the utility of the partition according to the invention by which the said loops are prevented from meeting and from becoming knotted or entangled;

Fig. 2 is a diagrammatic plan view showing the same stage as Fig. 1;

Fig. 3 is a side elevation, in the inverted position, of a needle plate which is provided according to the invention, with a stationary partition separating the loops which are formed;

Fig. 4 shows a movable partition mounted on the support of the hook which draws forward the cloth;

Fig. 5 is a separate perspective view of the partition shown in Fig. 4.

Fig. 1 represents the loopers 10 and 11 with respective hooks A and B, said loopers being separated from their supports 12—13 by the

pieces (known per se) which are designated as loop stretchers 14—15. In the recesses in the said loopers are mounted the cop holders 18—19 containing the cops upon which is wound the cop yarn, whose ends are observed at 20 and 21.

The loopers are rotated by the respective pinions 22—23, driven by the pinions 24—25 mounted on the horizontal driving shaft 26; these pinions rotate in the direction of the arrow f_1 .

The figures also show the tension device 27 which is apertured at 28 and 29; by a pivoted arrangement, known per se, the said tension device is given a vertical reciprocating motion whose period is represented by the total rotation of the flywheel shaft 30. By means of suitable gearing, the shaft 26 is rotated at double the speed of the shaft 30. Fig. 1 further represents the tension devices 31—32 carrying the yarn which proceeds to the needles 33—34.

In the stage of movement shown in Fig. 1, the needles 33 and 34 begin to descend. The hooks A and B, when turning on their axes, have formed the loops C and D; the tension 75 device 27, which is slowly rising, is about to finish its stroke by a sudden and rapid movement.

The loops C and D are then entirely as shown in the drawings thrown off their loopers, and under the action of the tension device they rise towards the cloth, forming stitches with the parts 20 and 21 of the cop yarn, thus producing the stitches. However at the time at which they are released from their loopers, 80 the loops C and D have as observed a considerable length, such as is necessary for their free release from each looper.

At this time, if the speed of the machine exceeds a certain limit, it is shown by experience that these loops are each thrown towards the vertical plane of symmetry of the loopers. The loops will thus meet in a violent manner, become entangled and will break when the tension device rises suddenly the next moment.

To obviate this drawback, the invention consists in disposing on the machine, at the point at which the loops tend to meet one 100

another, a partition adapted to separate the said loops.

In Figs. 1 and 2, the said partition is shown at 36, and it consists of a plate of suitable form mounted on the needle plate 35 and against the guide rod of the needles 37. Due to the said partition, as shown in the plan view Fig. 2, which corresponds to Fig. 1, the loops C and D will strike against the small plate 36, without meeting or tangling.

Fig. 4 shows another embodiment of the invention in which the metal plate 36' forming the partition is removable. Below the needle plate 35 is feed dog 40, and its support 41. Herein the small removable separating plate 36' is fixed to the feed dog support by the screws 43, and it is inserted through a hole formed in the feed dog; it is quite distinct from the needle plate.

Fig. 5 is a perspective view of the said small plate or partition 36' which obviously forms a sufficient separation between the two needles to prevent all contact between the yarn loops.

The machine which is provided with the said partition according to the invention will be enabled to operate at very high speeds without any breakage of the yarn.

In the following claims, the word "partition" relates to a device which is distinct from the guide-rod 37 for the needles, and is mounted in the machine in addition to this guide-rod, when the machine employs such a guide-rod. The "partition" may be formed upon the guide rod itself, as disclosed, or may be otherwise disposed. Obviously, the invention is not limited to machines employing such a guide-rod.

What I claim is:

1. A sewing machine of the type described provided with a needle guide rod comprising in combination two loopers adapted to rotate in opposite directions, a needle plate, and a partition plate mounted on said needle plate between said loopers adjacent said needle guide rod and extending in the direction in which the cloth is moving beyond the point at which the loops formed by the needle threads tend to make contact with each other when released from the loopers, whereby said loops are prevented from becoming entangled at that point when the machine is working at high speed.

2. A sewing machine of the type described provided with a needle guide rod, comprising in combination, two loopers adapted to rotate in opposite directions, a needle plate, and a partition plate mounted on said needle plate between said loopers adjacent said needle guide rod and extending in a direction opposite to the direction in which the loopers move when the distance between them is minimum, beyond the point at which the loops formed by the needle threads tend to make contact with each other when released from

the loopers, whereby said loops are prevented from becoming entangled at that point when the machine is working at high speed.

In testimony whereof I have signed this specification.

JACQUES OLLENDORFF.
